UNITED STATES PATENT OFFICE.

AXEL JOHNSON, OF OAKLAND, CALIFORNIA, ASSIGNOR TO AMERICAN CAN COMPANY, OF SAN FRANCISCO, CALIFORNIA, A CORPORATION OF NEW JERSEY.

APPARATUS FOR MARKING CAN ENDS AND POSITIONING THE SAME UPON CAN-BODIES.

1,371,685.

Specification of Letters Patent. Patented Mar. 15, 1921.

Application filed March 24, 1917. Serial No. 157,259.

To all whom it may concern:

Be it known that I, AXEL JOHNSON, a citizen of the United States, residing at Oakland, in the county of Alameda and State of California, have invented certain new and useful Improvements in Apparatus for Marking Can Ends and Positioning the Same upon Can-Bodies, of which the following is a specification.

- 10 The present invention relates to an automatic apparatus for marking or stamping can ends and for positioning the same upon can bodies in preparation for subsequent operations, as, for example, seaming.
- 15 The object of the invention is to provide a machine in which the described operations are performed by continuously moving mechanism, and in which the can bodies are received without regard to time or space,
- 20 and are placed in timed and spaced relation during their travel through the machine. By providing continuously moving parts the machine is enabled to operate with less wear and tear than is the case in machines whose
- 25 mechanism operates intermittently. Greater speed may also be attained in a continuous machine. Other objects will become apparent from the following description when read with reference to the drawings.
- 30 In order to understand the invention, reference should be had to the accompanying sheets of drawings, in which—

Figure 1 is a plan view of the machine, showing the can body and the can end feeding mechanism, and the device for marking the can ends.

Fig. 2 is a central longitudinal sectional view of the machine taken on the line 2—2 of Fig. 1, and viewed in the direction of the arrows, showing the can feeding mechanism, the can and can end advancing turrets, the marking device, and the associated driving mechanism.

Fig. 3 is a sectional plan view taken on the line 3—3 of Fig. 2, showing the can feeding mechanism and the can and can end advancing mechanisms.

Fig. 4 is a transverse sectional view, on an enlarged scale, taken on the line 4—4 of Fig. 1, and viewed in the direction of the arrows, disclosing in detail the can end feeding mechanism.

Fig. 5 is a sectional detail taken on the line 5—5 of Fig. 4, and viewed in the direction of the arrows, certain parts being broken away for the sake of clearness.

Fig. 6 is a sectional detail of the can end feeding mechanism, taken on the line 6—6 of Fig. 1 and viewed in the direction of the arrows, showing a can end being removed from the stack of can ends.

Fig. 7 is a sectional detail of the can end marking mechanism, taken on the line 7—7 of Fig. 1 and viewed in the direction of the arrows, showing a can end in position between the marking dies and the relative position of the can and end at such time.

Fig. 8 is a fragmental detail plan of the parts shown in Fig. 7.

Fig. 9 is a sectional detail taken on the line 9—9 of Fig. 1 and viewed in the direction of the arrows, showing the assembling of the can end upon the can.

In the drawings, the reference numeral 1 designates a suitably constructed frame upon which the entire mechanism of the apparatus is mounted. The frame 1 supports a horizontal table 2, onto which the can bodies 3, Figs. 1, 2 and 3 of the drawings, are introduced in any manner, not illustrated, and above which are guide rails 4, for guiding the cans 3, as the same are introduced onto said table 2. A can feed wheel 5 is horizontally mounted above the left-hand or feed end of the table 2, and is carried upon a vertical shaft 6, which is journaled at 7 in the table 2, as shown in Fig. 2 of the drawings, and which carries upon its lower end a spur-gear 8, said spur-gear being adapted to mesh with a spur-gear 9, carried upon a vertical shaft 10, journaled at 11 and 11', in the table 2 and the frame, respectively, and carrying upon its lower end a bevel-gear 12. Said bevel-gear is adapted to mesh with and be driven by a bevel-gear 13 mounted upon a horizontally disposed drive shaft 14, suitable mounted in the frame 1, and carrying a pulley 15 adapted to receive power from an outside source, not shown in the drawings. The can feed wheel 5 is formed, as shown in Figs. 1 and 3 of the drawings, with a plurality of peripheral can engaging pockets 16, adapted to engage the cans 3 at the positions A, Fig. 3 of the drawings, as the same are advanced between the guide rails 4, and to move the same forwardly in the desired timed and spaced relation, as shown at a in Fig. 1 of the drawings. A yielding guide-rail 17 is provided to retain the cans 3 in proper engaging relation with the can feed wheel 5. Said guide

100

105

110

rail is supported by means of springs 18, so that if a can should become misplaced with respect to the pockets 16 of the can feed wheel 5, the guide rail will give enough 5 to prevent the crushing of the can between the guide rail and said feed wheel 5.

The vertical shaft 10 carries, above the table 2, a turret 19, Figs. 1, 2, 3, 4 and 6 of the drawings, comprising a pair of parallel 10 spaced horizontally disposed disks 20, having can receiving pockets 21 formed in their outer edges. These pockets of the disks 20 are adapted to receive the cans 3, from the feed wheel 5 at the position B, Fig. 3, and 15 to further continuously advance the same within a semi-circular guide rail 22.

A third vertical shaft 23, Figs. 1, 2 and 3 of the drawings, is rotatably carried at 23' in the table 2, preferably in the same 20 plane with the shafts 6 and 10. Said shaft 23 carries upon its lower end a spur-gear 24, Fig. 2 of the drawings, adapted to mesh with and be driven by the gear 9 upon the shaft 10. Thus all three vertical shafts 25 rotate in timed relation, and are driven by the main drive shaft 14. The shaft 23 carries, above the table 2, a turret 25, Figs. 1 and 2 of the drawings, comprising spaced upper and lower disks 26, Fig. 2 of the drawings, 30 formed with aligned can receiving pockets 27 in their edges. The turret 25 is adapted to receive the cans from the turret 19 at the position C, Fig. 3 of the drawings, and to further advance the same continuously, 35 within a suitably formed guide member 28, Figs. 1 and 3 of the drawings.

In the drawings, I have illustrated a portion of the machine to which the cans are fed by the apparatus comprising my invention. This machine may perform any desired operation upon the cans, as, for example, seaming, and is shown as having a 40 rotatable turret 29, Figs. 1, 2 and 3 of the drawings, mounted upon a suitably formed base 30, positioned adjacent to the right hand end of the frame 1. The turret 29 is shown as provided with a vertical shaft 31, which is driven by the drive shaft 14 through a pair of meshing bevel-gears 32. 45 The turret 29 is also shown as provided with can engaging pockets 33, Figs. 1, 2 and 3 of the drawings, within which the cans are placed by the second advancing turret 25, at the position D, Fig. 3, and by which they 50 are carried onward for whatever subsequent operation may be performed upon them.

It will be seen that the path of the can bodies through the machine is circuitous, 60 as indicated by the arrows in Figs. 1 and 3 of the drawings. Said can bodies as received between the guide rails 4, are engaged and placed in timed and spaced relation by the can feed wheel 5, and are

advanced continuously and successively, by 65 said feed wheel and the turrets 19 and 25, and are finally placed by the latter upon the turret 29 in the proper timed relation.

Above the turrets 19 and 25, and spaced 70 above the table 2, is a fixed plate 34, Figs. 1, 2, 4 and 6 of the drawings. A magazine or holder adapted to contain a stack of can ends is carried by said plate 34, and comprises a horizontally disposed ring 35, from which parallel spaced rods 36 extend 75 upwardly. The can ends 37 are placed within said holder in stack formation, one resting upon the other, and the lowermost can end of the stack resting upon shoulders 38, Fig. 4 of the drawings, formed at the upper 80 edge of an aperture 39 in the plate 34. The plate 34 has formed on its underside a cylindrical flange 40, Figs. 4, 6, 7 and 9 of the drawings, surrounding the upper portion of the turret 19, in the inner surface of 85 which is formed a spiral groove 41; and within the upper plate 20 of the turret 19 is a fixed hub 42, Fig. 4, secured to and extending downwardly from the plate 34, and having formed in its exterior wall a spiral 90 groove 43, which lies in the same horizontal plane at all points as the groove 41 in the outer flange 40. These grooves terminate at their upper ends at the shoulder 38, at the bottom of the can end magazine, and form a 95 spiral track into which the lowermost can end is removed from the magazine or holder, as shown at 37' in Fig. 6, and by which said can end is guided in a spiral path to a plane lower than that of the bottom of the magazine, and into a position in vertical alignment with the can body 3 at the point of transfer from the turret 19 to the turret 25, that is, at the position C, Fig. 3 of the drawings.

The upper disk 20 of the turret 19 carries 100 a pair of vertically slidable plungers 44, Fig. 4 of the drawings, mounted upon the upper ends of the vertically disposed rods 45. The rods 45 extend through the lower disk 20 105 of the turret 19 and are slidably carried therein, and the lower ends of said rods are provided with heads 46, which extend radially beyond the edge of the turret disk 20 and carry outwardly projecting cam rollers 47. Springs 48 are provided to retain the plungers 44 and their rods 45 in their uppermost positions so that, upon the rotation of the turret 19, said plungers will successively engage the lowermost can end of 110 the stack of ends within the magazine and slide the same laterally out from beneath said stack into the spiral grooves 41 and 43, and will advance the end within said grooves to the lower end thereof. To insure 115 the proper removal of the can end from the magazine, and its entrance into said spiral grooves, the plungers 44 are provided with 120 125

laterally extending hooks 44', Figs. 4 and 6, adapted to enter between the lowermost end 37', Fig. 6, and the end next above.

The inner walls of the upper parts of the pockets 21 are removed to expose to the edges of the can ends the hub 42 and its spiral guide or groove, and these parts of the pockets are enlarged down to the top of the can body so as to accommodate the slightly greater diameter of the can end (Fig. 6). The plunger 44 is only required to propel the can end until the spiral grooves have carried it down into the top of the pocket 21 and thereafter the wall of the pocket will engage and propel it until it is carried out of said grooves and on to the can body.

Mounted upon the table 2, for horizontal swinging movement, is a bell-crank lever 49, Figs. 1, 3 and 4 of the drawings, one arm 49' of which normally lies within the path of the can bodies as the same are advanced by the feed wheel 5. The other arm of said bell-crank lever carries on its end a cam member 51, Figs. 2, 4, 5 and 6 of the drawings, which normally lies in the path of the cam rollers 47 carried by the lower ends of the end feed plunger rods 45. When the bell-crank lever is in its normal position, in which it is retained by a spring 52, Figs. 1 and 3 of the drawings, the cam rollers 47 ride upon the cam 51 carried by the end of said bell-crank lever, and depress the plunger heads 44 as the same are carried under the can end magazine, to prevent said plunger heads from engaging the lowermost can end within said magazine, as shown in Fig. 4 of the drawings. Thus, if no can body is advanced by the feed wheel 5, the bell-crank lever will not be moved, and no can end will be removed from the magazine; but if a can body is advanced by said feed wheel, and engages the end 49' of the bell-crank lever, the other end thereof will be moved out of the path of the cam rollers 47, and the end feed plungers 44 will be retained in their uppermost positions by their springs 48. A can end will in this case be removed from the magazine, as shown in Fig. 6 of the drawings, and carried within the spiral grooves into a position for placing upon the can body in a manner to be presently described. A swinging latch member 53, Figs. 4 and 5 of the drawings, is carried by the lower turret disk 20 adjacent to the lower end of each end feed plunger rod 45. The outer end of said latch is adapted to bear against the side of the head 46 carried upon the lower end of said plunger rod, and is so held by a spring 54, so that when the plunger rod is depressed by the engagement of its cam roller 47 with the cam 51, carried by the bell-crank lever, said latch member 53 is moved inwardly against the lower end of the rod 45, above the head 46 thereof, and thereby retains said rod and the end

feed plunger carried thereby in their lowermost position, so that said plunger will not be elevated against the lowermost can end within the magazine, even after the cam roller 47 has run free of the cam 51. A pin 55 extends upwardly from the table 2 and is adapted to engage the inner ends of the latch members 53, as shown in Figs. 4 and 5 of the drawings, to move said latch members out of engagement with the heads 46 of the plunger rods 45, to allow said rods to be returned to their uppermost positions by their springs.

The can ends are marked or stamped with any desired legend or mark, immediately after leaving the magazine. For this purpose, a bracket 56, Figs. 1, 2 and 8 of the drawings, is pivotally mounted at 57, on a hub extending upwardly from the upper fixed plate 34 and surrounding and providing a journal for the upper end of the turret shaft 10. The bracket 56 extends over the edge of said plate 34, as shown, and carries an inwardly turned lower end 58, Fig. 2 of the drawings, lying under said plate and beneath the plane of the spiral can end grooves 41 and 43. Said inwardly turned end 58 carries a die-plate 59 over which the can ends pass in close relation. A die 60 is carried within a suitable guide 61, Figs. 2, 7 and 9 of the drawings, in the upper portion of the bracket 56, in vertical alinement with the lower die plate 59, said die being normally retained by a spring 62 in a position slightly above the can end 37' passing within the spiral grooves, as shown in Fig. 7. The upper end 63 of the die 60 extends above the bracket 56 and is adapted to be struck by a hammer 64 carried upon the end of a lever 65, Figs. 1 and 2 of the drawings, mounted upon a bracket 66 rising from the upper fixed plate 34. A cam roller 67 is mounted upon the hammer lever 65 and is adapted for engagement by a face-cam 68 carried by the upper end of the vertical shaft 10, Figs. 1, 2 and 4 of the drawings. By means of said cam the hammer 64 is actuated to strike the die 60 at the proper time to stamp each can end 37' passing beneath said die. In order to allow enough time for the proper stamping of the can end, the bracket 56 is freely movable about its support at 57, and therefore travels with said can end for a limited distance as long as the die 60 is in engagement therewith. A spring 69, Fig. 8 of the drawings, is provided to return the bracket 56 to its initial position upon the raising of the hammer 64 and the release of the die from the can end.

As before stated, a can body is engaged by the can feed wheel 5 at position A of Fig. 3 of the drawings, and is advanced by said feed wheel to the position B, at which it is transferred to the first advance turret 19, and moved thereby to the position C. 130

During the movement of the can body from the position B to the position C, a can end, which has been removed from the magazine 35, is advanced along the spiral grooves 41 and 43, to occupy a position in vertical alinement with and immediately above the can body at the position C. The spiral grooves 41 and 43 terminate at this point, so that the can end is free to move upon the can body in axial alinement therebeneath. In order to insure the proper placing of the end upon the can body, there is provided a vertically movable weight 70, Figs. 1, 2 and 9 of the drawings, carried by a pair of spaced levers 71, Figs. 1 and 2 of the drawings, pivotally connected at 72 with brackets 73 extending upwardly from the fixed plate 34. Said levers carry cam rollers 74 adapted to ride upon a face-cam 75 carried by the upper end of the vertical turret shaft 23. Thus the weight 70 is actuated by the cam 75 to strike each can end at position C and to position said end positively upon the can body beneath. To limit the downward movement of said assembling weight 70, I provide a stop 76, Figs. 2 and 9 of the drawings, preferably slightly resilient in its nature, upon which said weight strikes.

The can body, with the end positioned thereupon, is then advanced from the position C to the position D, Fig. 3 of the drawings, by the second advance turret 25, and there placed upon the turret 29 of the succeeding machine, as previously described.

A plate 77, Figs. 1, 2 and 3 of the drawings, closely overlies the can and its end during their advance to the position D, and prevents the end from being displaced during this movement.

The operation of the machine may be briefly summarized as follows:—

A stack of can ends is placed within the magazine 35 and 36, Fig. 4 of the drawings, the lowermost end thereof resting upon the shoulder 38, at the upper end of the spiral grooves 41 and 43. The can bodies are introduced into the machine between the guide rails 4, Fig. 3, and as each can engaging pocket 16 of the can feed wheel 5 comes to the position A, a can body is engaged thereby and is advanced to the position B. During this advance, the can body actuates the bell-crank lever 49 to enable one of the end feed plungers 44 of the first advance turret 19, to engage the lowermost can end in the magazine and to carry the same out from beneath said magazine and into the spiral grooves. The can body is now transferred to the first advance turret 19 and is advanced thereby to the position C, and at the same time the can end which, has been removed from the magazine, is also advanced, through the spiral grooves, and placed above the can body and in axial alinement therewith at the position C. The can end,

after leaving the magazine, and before reaching the position C, is stamped by the die 60, which is actuated by its hammer 64. At the position C the weight 70 is allowed to fall upon the can end and to place the same positively upon the can body. The can body, with its end resting thereupon, is thence carried forward by the turret 25 and placed upon the turret 29 of the succeeding machine at the position D. If no can is engaged and advanced by the can feed wheel 5, the bell-crank lever 49 will not be actuated, and no end will be removed from the magazine.

It is to be particularly noted that the travel of the can bodies, from the time they are engaged by the feed wheel 5 until they are discharged upon the succeeding machine, is continuous, there being no pause or sudden change of direction. Similarly the can ends are continuously advanced from the magazine, the marking and assembling thereof with the can bodies being accomplished without interrupting said continuous advancing movement.

The invention has been hereinbefore described and is herewith illustrated in its preferred form. However, I do not wish to be construed as limiting myself thereto, for the reason that changes of form and construction may be made without departing from the spirit of the invention, and I therefore wish to be understood as claiming the invention as broadly as the state of the art will permit.

Having thus described the invention, what I claim as new and desire to be protected by Letters Patent is:—

1. In an apparatus for the described purpose, means for advancing a series of can bodies, means for holding a stack of can ends above the can body advancing means in alinement over the path of the can bodies, and devices for removing the lowermost end from the stack within the holding means and advancing the same in a spiral path into axial alinement with the advancing can body.

2. In an apparatus for the described purpose, means for advancing a can body, a holder adapted to contain a stack of can ends arranged in alinement over the path of the can body, and devices for removing the lowermost end from the stack within said holder, and for conveying the same in a spiral path into axial alinement with the advancing can body, said spiral path being formed by inner and outer spirally grooved cylindrical walls.

3. In an apparatus for the described purpose, means for advancing a can body, a holder adapted to contain a stack of can ends arranged in alinement over the path of the can body, devices for removing the lowermost end from the stack within said

holder and for conveying the same in a spiral path into axial alinement with said can body, and means for assembling said can end and said alined can body, said spiral path being formed by inner and outer inclined guides having different angles of inclination.

4. In an apparatus for the described purpose, means for advancing a can body, a holder adapted to contain a supply of can ends arranged in alinement over the path of the can body, a spiral track adapted to guide an end from said holder into axial alinement with the advancing can body, and means for removing an end from said holder and conveying the same along said spiral track, and marking means operating on the can ends while held in said track.

5. In an apparatus for the described purpose, means for advancing a can body, a holder adapted to contain a supply of can ends arranged in alinement over the path of the can body, a spiral track having inner and outer spiral elements adapted to guide an end from said holder into axial alinement with the advancing can body, devices for removing an end from said holder and conveying the same along said spiral track, and means for removing said can end from said spiral track and placing the same upon said can body, and marking means operating between the inner and outer spiral elements of said track.

6. In an apparatus for the described purpose, rotary means for advancing a can body, a holder adapted to contain a supply of can ends arranged in alinement over the path of the can body, and devices associated with said rotary can advancing means for removing a can end from said holder, advancing the same in a spiral path co-axial with said rotary means, and positioning the same upon said can body, said spiral path being formed by an outer spirally grooved vertical flange and an inner spirally grooved hub.

7. In an apparatus for the described purpose, means for advancing a can body, a holder adapted to contain a stack of can ends, positioned above said can body advancing means in alinement over the path of the can body, and devices associated with said advancing means for removing the lowermost end from the stack within said holder and conveying the same in a downwardly inclined path into a position in axial alinement above said can body.

8. In an apparatus for the described purpose, means for advancing a can body, a holder adapted to contain a supply of can ends, positioned above said can body advancing means in alinement over the path of the can body, and devices associated with said advancing means for removing a can

end from said holder and conveying the same in a downwardly inclined path to the path of said can body, and for positioning the same upon said can body.

9. In an apparatus for the described purpose, rotary means for advancing a can body, a holder adapted to contain a supply of can ends, positioned above said advancing means in alinement over the path of the can body, devices associated with said advancing means for removing a can end from said holder and conveying the same in a downwardly inclined spiral path to the path of the advancing can body, and means for assembling said can end and said can body.

10. In an apparatus for the described purpose, means for advancing a can body, a holder adapted to contain a supply of can ends, devices for removing an end from said holder and conveying the same in a spiral path into axial alinement with the advancing can body, and mechanism for marking said can end during the spiral travel thereof, said marking mechanism having a movement accompanying the can end during the marking action and thence returning to initial position.

11. In an apparatus for the described purpose, means for advancing a can body, a holder adapted to contain a supply of can ends, devices for removing an end from said holder and conveying the same in a spiral path into a position in axial alinement with said advancing can body, and mechanism actuated by said advancing means and adapted for limited movement therewith for marking the advancing can end, and comprising marking devices which are reciprocatory forward with the can end and thence backward.

12. In an apparatus for the described purpose, means for advancing a can body, a holder adapted to contain a supply of can ends, devices for removing an end from said holder and conveying the same into a position in axial alinement with said can body, and mechanism actuated by the can body and can end, advancing means for marking the advancing end, said mechanism having dies which are reciprocatory in the lines of travel of the can end and are adapted to move in unison with said end during the marking thereof.

13. In an apparatus for the described purpose, means for advancing a can body, a holder adapted to contain a supply of can ends, devices associated with said can body advancing means for removing an end from said holder and conveying the same into a position in axial alinement with the advancing can body, mechanism associated with the advancing means for marking the advancing can end, said mechanism having dies adapted to travel in unison with said can

end during the marking thereof, and comprising means for moving said dies toward the can end and then with the can end in its travel and then away from the can end and 5 then reversely to the can end.

14. In an apparatus for the described purpose, means for advancing a can body, a holder adapted to contain a supply of can ends, devices associated with the can body 10 advancing means for removing an end from said holder and conveying the same into a position in axial alinement with said advancing can body, mechanism for marking the advancing can end, said mechanism having 15 oscillatory dies adapted to travel in unison with said can end during the marking thereof, and means for placing the marked can end upon the can body.

15. In an apparatus for the described purpose, 20 means for receiving a series of can bodies and advancing the same in timed and spaced relation, a holder adapted to contain a stack of can ends, devices for removing successively the lowermost can end of the 25 stack within said holder and conveying said ends successively into a position in axial alinement with the advancing can bodies, mechanism having oscillatory marking devices movable parallel with the can ends for 30 marking each can end as the same is conveyed from the holder, devices for placing the marked can end upon the can body positioned in axial alinement therewith, and means for discharging the can body and the 35 can end positioned thereupon in timed and spaced relation.

16. The combination of can body feeding mechanism, can end feeding mechanism, can 40 end applying mechanism, and means for marking said can ends provided with marking members which are reciprocable toward and from the can end, and with an opposite to the movement of the can ends, and means for actuating said marking members.

- 45 17. The combination of can body feeding mechanism and can end feeding mechanism arranged to propel the said ends and bodies in unison and alinement, can end guiding means inclining toward the path of said bodies, can end applying mechanism, and means for marking said can ends provided with marking members which are reciprocable toward and from the can end, and with 50 and opposite to the movement of the can ends, and means for actuating said marking members.

- 55 18. The combination of can body feeding mechanism, can end feeding mechanism comprising a stack holder and a vertically 60 movable can end propelling device movable also with the can bodies, can end applying mechanism, and means for marking said can ends provided with marking members which are reciprocable toward and from the

can end, and with and opposite to the movement of the can ends, and means for actuating said marking members. 65

19. The combination of can body feeding mechanism, can end feeding mechanism, comprising a stack holder and a vertically 70 movable can end propelling device movable also with the can bodies, can end applying mechanism, and means for marking said can ends provided with marking members which are reciprocable toward and from the can 75 end, and with and opposite to the movement of the can ends, means for actuating said marking members, and means engageable by a can body for holding said propelling device retracted from the stack holder to prevent its engagement with a can end when 80 not so engaged.

20. The combination of means for advancing can bodies, can end guides extending in the direction of the advance of said 85 can bodies and to a point near the path of the same, means for advancing in unison each can end with its corresponding body reciprocable marking means movable with said can bodies and ends during the marking 90 action and adapted to operate on said ends without retarding their advance, and means for causing the marked ends to be applied to the can bodies.

21. The combination of means for advancing can bodies, can end guides inclining in the direction of the advance of said can bodies and also toward the path of the same, means for advancing in unison each can end with its corresponding body, marking means 100 movable with said can bodies and ends during the marking action and adapted to operate on said ends without retarding their advance, and means for causing the marked ends to be applied to the can bodies. 105

22. The combination of means for advancing can bodies, can end guides extending in the direction of the advance of said can bodies and to a point near the path of the same, means for advancing in unison each can end with its corresponding body, marking means movable with said can bodies and ends during the marking action and also oppositely movable, and adapted to operate on said ends without retarding their 110 advance, and means for causing the marked ends to be applied to the can bodies. 115

23. The combination of means for advancing can bodies, can end guides extending in the direction of the advance of said 120 can bodies and to a point near the path of the same, means for advancing in unison each can end with its corresponding body, marking means and a holder for the same extending on both sides of the path of the 125 can ends and movable with said can bodies and ends during the marking action and adapted to operate on said ends without re-

tarding their advance, and means for causing the marked ends to be applied to the can bodies.

24. The combination of means for advancing can bodies, can end guides extending in the direction of the advance of said can bodies and to a point near the path of the same, means for advancing in unison each can end with its corresponding body, marking means movable with said can bodies and ends during the marking action and adapted to operate on said ends without retarding their advance, means for retracting said marking means in a direction substantially parallel with the path of the can ends, and means for causing the marked ends to be applied to the can bodies.

25. The combination of means for advancing can bodies, can end guides extending in the direction of the advance of said can bodies and to a point near the path of the same, means for advancing in unison each can end with its corresponding body, marking means movable with said can bodies and ends during the marking action and adapted to operate on said ends without retarding their advance, a hammer for actuating a marking element, and means for causing the marked ends to be applied to the can bodies.

26. The combination of a carrier having can body and can end receiving and propelling pockets, fixed parts at the inner side and at the outer side of said pockets having circular can end guides which decline at different angles toward the path of the can bodies, and means for feeding can ends to said guides and pockets.

27. The combination of a rotary turret having can body and can end receiving and propelling pockets, fixed parts at the inner side and at the outer side of said pockets having circular can end guides which decline at different angles toward the positions of the can bodies, and means for feeding can ends to said guides and pockets.

28. The combination of a rotary turret having can body and can end receiving and propelling pockets, fixed parts at the inner side and at the outer side of said pockets having circular can end grooves which decline at different angles toward the positions of the can bodies, and means for feeding can ends to said guides and pockets.

29. The combination of a rotary turret having can body and can end receiving and propelling pockets, fixed parts at the inner side and at the outer side of said pockets having circular can end guides which decline at different angles toward the positions of the can bodies, a fixed can end holder, and means carried by the turret for feeding can ends to said guides and pockets.

30. The combination of a rotary turret having can body and can end receiving and

propelling pockets, fixed parts at the inner side and at the outer side of said pockets having circular can end guides which decline toward the positions of the can bodies, means carried by the turret for feeding can ends to said guides and pockets, and means carried by the turret for holding said feeding means in inoperative position.

31. The combination of a carrier having can body and can end receiving and propelling pockets, fixed parts at the inner side and at the outer side of said pockets having circular can end guides which decline toward the positions of the can bodies, means carried by the said carrier for feeding can ends to said guides and pockets, and means engageable by a can body for moving said feeding means to inoperative position when not so engaged.

32. A can body and can end carrier having pockets for receiving and propelling can bodies and can ends above said bodies, means engaging the edges of the can ends for feeding can ends downward in said pockets to the can bodies during the carrying of the latter, and means for feeding can ends downward from a stack to said pockets.

33. A can body and can end carrier having pockets for receiving and propelling can bodies and can ends above said bodies, means for feeding can ends downward in said pockets to the can bodies during the carrying of the latter, means for feeding can ends downward from a stack to said pockets, and marking devices having an element arranged between the paths of the can body and can end and an element arranged above the path of the can end.

34. A can body and can end carrier having pockets for receiving and propelling can bodies and can ends above said bodies, means for feeding can ends downward in said pockets to the can bodies during the carrying of the latter, means for feeding can ends to said pockets, and devices movable by a can body for rendering inoperative said feeding means which supplies can ends to said pockets when not so moved by a can body.

35. The combination of a rotary turret for advancing can bodies and can ends, marking devices both above and below the path of the can end, and supporting means for the marking devices extending both above and below the path of the can end and pivotally connected at the axis of said turret.

36. The combination of a can body supporting table, a can body spacing and feeding rotary wheel mounted thereover and having can receiving and propelling pockets, a can body feeding continuously rotary turret having can body and can end receiving pockets registering with the pockets of said wheel and co-operating therewith to en-

gage the can bodies successively at a transfer station, a second continuously rotary turret having pockets registering with those of the first turret to receive the can bodies from the latter at a second transfer station, can guiding means for holding the can bodies in said pockets, means for feeding can ends above the can bodies at said first station, means supported coaxially with the 5 turret for marking the can ends near said first station, means for maintaining the can ends above the can bodies between said stations and guiding them into contact with the can bodies at said second station, and 10 means for applying the can ends on to the can bodies at said second station.

37. The combination of a can body supporting table, a can body spacing and feeding rotary wheel mounted thereover and 20 having can receiving and propelling pockets, a can body feeding continuously rotary turret having can body and can end receiving pockets registering with the pockets of said wheel and coöperating therewith to engage the can bodies successively at a transfer station, a second rotary turret having 25 pockets registering with those of the first turret to receive the can bodies from the latter at a second transfer station, can guiding means for holding the can bodies in said pockets, means for feeding can ends above the can bodies at said first station, means supported coaxially with the 30 turret for marking the can ends near said first station, means for maintaining the can ends above the can bodies between said stations and guiding them into contact with the can bodies at said second station, means for forcing the can ends on to the can bodies 35 at said second station, and means for maintaining the can ends in applied position while they are carried by said second turret.

38. The combination of a can body supporting table, a can body spacing and feeding rotary wheel mounted thereover and 45 having can receiving and propelling pockets each having a curvature of about a quarter of a circle, a can body feeding continuously rotary turret having can body and can end receiving pockets of a curvature of 50 about a half of a circle registering with the pockets of said wheel and coöperating therewith to engage the can bodies successively at a transfer station, a second rotary 55 turret having pockets registering with those of the first turret to receive the can bodies from the latter at a second transfer station, can guiding means for holding the can bodies in said pockets, means for feeding can ends above the can bodies at said 60 first station, means supported coaxially with the turret for marking the can ends near said first station, means for maintaining the can ends above the can bodies between said

stations and guiding them into contact with the can bodies at said second station, means for applying the can ends on to the can bodies at said second station.

39. The combination of means for feeding and propelling can ends to be applied 70 to can bodies, means for embracing above and below and guiding two opposite edges of the can ends while they are propelled, marking means arranged at opposite sides of the path of the can ends to operate on said 75 ends while they are embraced and held from vertical displacement by said guiding means, and means for feeding can bodies to receive said can ends.

40. A can end feeding means having, in 80 combination, a rotary turret provided with can end holding and propelling pockets, a fixed member within said turret having a can end guiding spiral groove, and a fixed part without said turret having a can end 85 guiding spiral groove.

41. A can end feeding means having, in combination, a rotary turret provided with can end holding and propelling pockets, a fixed member within said turret having a 90 can end guiding spiral groove, and a fixed part without said turret having a can end guiding spiral groove, and marking means arranged to act on the can ends while they are in said grooves.

42. The combination of means for advancing can bodies and can ends to uniting means, consisting of means for peripherally engaging can ends and supporting the same at their edges only and moving them 100 continuously toward and to said uniting means; movable marking means in the path of said can ends adapted to contact with said can ends and move in time therewith during the marking action and marking the 105 same without retarding their advance and means at said uniting station for uniting the marked can ends to can bodies.

43. The combination of means for advancing can bodies and can ends to uniting 110 means, consisting of means for peripherally engaging can ends and moving them continuously toward and to said uniting means and continuing said movement during the uniting operation; movable marking means 115 in the path of said can ends adapted to contact with said can ends and move in time therewith during the marking action and marking the same without retarding their advance and means at said uniting station 120 for uniting the marked can ends to can bodies.

In testimony whereof I have signed my name to this specification in the presence of a subscribing witness.

AXEL JOHNSON.

Witness:

N. A. ACKER.
